UNITED STATES PATENT OFFICE.

CHARLES FREDERICK WALZ AND FRANCIS DEVELIN MORRIS, OF PHILADELPHIA, PENNSYLVANIA, ASSIGNORS, BY MESNE ASSIGNMENTS, TO EDWIN WOLF, BENJAMIN WOLF, CLARENCE WOLF, LOUIS WOLF, AND ALBERT WOLF, ALL OF PHILADELPHIA, PENNSYLVANIA, COPARTNERS TRADING AS NATIONAL METAL EDGE BOX COMPANY, OF PHILADELPHIA, PENNSYLVANIA.

BOX-STAYING MACHINE.

1,346,573.

Specification of Letters Patent. Patented July 13, 1920.

Application filed July 28, 1919. Serial No. 313,761.

To all whom it may concern:

Be it known that we, CHARLES FREDERICK WALZ and FRANCIS DEVELIN MORRIS, citizens of the United States, residing at Philadelphia, county of Philadelphia, and State of Pennsylvania, have invented a new and useful Improvement in Box-Staying Machines, of which the following is a full, clear, and exact description, reference being had to the accompanying drawings, which form a part of this specification.

The invention relates to that class of machines in which a die is caused to descend upon a stationary anvil, between which is placed a box and stay or other articles to be clamped together or compressed.

In box staying machines, such as described in connection with my invention, the anvil is usually of rectangular cross section and positioned diamond-wise, with its horizontal active edge uppermost. Against this edge and contiguous surfaces the die descends and does its work.

The invention may, however, be applied with equal effectiveness to machines in which anvil and die present round or flat horizontal surfaces between which the compression takes place.

In the operation, for example, of staying a box angle, the operator places the two sides to form said angle upon the faces of the anvil contiguous to the active edge, and holds them close with his fingers during the action of the die in the application of the stay. This requires that the operator shall keep his fingers close to the joint and yet not too close. To decrease danger of accident and protect the operator, it is desirable to provide some safety device therefor.

The object of this invention is to provide such a safety device, wherein appropriate parts are supplied, carried by the die-holder and projecting downwardly in advance of the die, and so positioned as to contact with the operator's fingers if he has inadvertently placed them within the danger zone, and thereby be so moved relatively to the die as to disrupt the driving connections to the die-holder so that the latter will cease to be positively moved downward.

This object has heretofore been attained by means that would come within the broad

language of the foregoing description; but the safety devices of the prior art have been so complicated as to frequently get out of order and hence their action has been uncertain and unreliable. The more specific object of this invention is to so simplify the safety mechanism actuatable by the finger guard as to materially reduce the likelihood of the parts getting out of order and, in all circumstances, to insure safety to the operator.

A preferred embodiment of the invention is shown in the drawings, in which—

Figure 1 is a side elevation of a part of a box staying machine with the invention applied thereto.

Fig. 2 is a plan view, partly in section, of the die-holder and guide therefor.

Fig. 3 is an end view of the die, anvil and finger guard.

Over the anvil *a* is a die *b* carried by a vertically reciprocatory die-holder *c*. A metal staying strip (not shown) is fed from a roll, by appropriate mechanism, over the anvil *a* and under the die *b*. This mechanism is well known and forms no part of the invention and is therefore not shown. The box or box blank to be reinforced is placed on the anvil, and the die, in its descent, applies the staying strip to the box angle.

Pivoted on the machine frame is a lever *d*. The swinging end of the lever is connected to the die-holder *c* by means of a link *e*. A connecting rod *g* is reciprocated up and down by means of actuating mechanism which is usual in this class of machines and is therefore not illustrated. The upper end of the connecting rod *g* is connected with the joint between lever *d* and link *e* by a link *f*.

This die-actuating mechanism is old and common except that it is customary to make the lever *d* and link *f* as a single or unitary elbow lever. Hence the upper end of the connecting rod *g*, in its up and down movement, swings always on the axis of lever *d*, which, with link *e*, forms a toggle joint to positively actuate the die-holder *c* and die *b* in the downward movement of the connecting rod *g*.

In the present construction, which it is desired shall have normally the same mode

of operation, provision is made for so locking the lever *d* to the link *f* that they normally move as a unit. Provision, however, is made for unlocking the lever *d* from the link *f* so that the link *f*, as the connecting rod *g* moves downward, is free to swing, on the end thereof that is pivoted to the toggle joint, independently of the lever *d* and therefore without forcibly depressing the die *b*.

- 10 A preferred form of releasable lock is the bell-crank lever *h*, *i* pivoted on the link *f*. One arm *h* of this locking lever has a hook *j* adapted to engage a corner of an arm *k* integral with the lever *d*. It is obvious that, 15 as the connecting rod *g* moves down, the hooked lever *h* is pulled down with it and the lever *d* is pulled down by the hooked lever. Thus, the link *f* and the lever *d* operate as a unit, causing the lever *d* and the link *e* to work as a toggle joint in the usual manner and positively lower the die *b*.

20 In the upward movement of the connecting rod, an adjustable screw 12 on the link *f* engages the arm *k* of the lever *d* and positively swings up the lever *d*, causing the toggle joint to operate, in the usual manner, to retract the die *b*.

25 From the foregoing description it is clear that if, in the downward movement of the rod *g*, the locking lever is independently actuated to cause its hooked arm *h* to swing out of engagement with the arm *k* of lever *d*, the die *b* will not be positively moved down. The disengagement of the locking lever is effected automatically, in case there is any obstruction (for example, an operator's finger) to the downward movement of the die, by the following mechanism.

30 A finger guard, of light frame construction, comprising yoke-shaped end pieces *n*, *n*, is carried by the die-holder, straddling the same at both ends. Connecting the end pieces are horizontally extending guarding rods *o*, *o*, on both sides of the die and 35 slightly in advance thereof. These rods are supported close to the working edge of the die, not close enough to interfere with the normal working of the machine, but sufficiently close to surely contact with the operator's fingers if they should be in dangerous position. This finger guard is a known contrivance. It is normally inoperative in that it moves up and down with the die *b*; but it is slidable vertically upward 45 and so operates when, in its downward movement, it encounters an operator's finger or any other obstruction. To insure that it shall move upward in a right line, a bar *p* connects the end pieces *n*, *n*. Back of connecting bar *p*, the die-holder carries two intermediately pivoted levers, *r*, *r*. The adjacent ends of these levers *r* have a pin and slot connection *s*. The opposite ends of the levers are slotted to engage pins *t*, *t* on the 50 bar *p*. If either end of the finger guard has

its movement arrested by an obstruction, the action of the levers *r* is to maintain the opposite end of the finger guard on the same level as the end which meets an obstruction. Therefore, one end of the finger guard can 55 not be tilted relatively to the other.

Assuming that, in the pressing movement of the die, the downward movement of the finger guard is arrested, and hence moved up relatively to the die, a knock-off rod *u*, 75 carried by the finger guard, engages the arm *i* of the locking lever and swings the arm *h* of the locking lever out of engagement with the arm *k* of the lever *d*, so that the lever *d* is no longer forcibly pulled down. Therefore there is no positive downward push 80 upon the die-holder and if it should move down farther by gravity and momentum, it might do no serious injury. However, it is deemed desirable to positively stop the 85 downward movement of the die. This may be effected in different ways. In Fig. 2, a ratchet 16 is secured to the machine frame. A lever, pivotally carried by the lever *h*, 90 has one arm 13 adapted to act as a pawl engageable with the ratchet 12 and another arm 14 in line of movement of a knock-off rod 15 carried by the finger guard. Assuming that the finger guard meets an obstruction in its downward movement, the first 95 action is for knock-off rod *u* to engage the arm *i* and disrupt the driving connection between link *f* and lever *d*, as before described. Immediately after this, knock-off rod 15 engages the arm 14 and swings the 100 pawl 13 into engagement with ratchet 16, thereby arresting the downward movement of lever *d* and die-holder.

In the normal operation of the machine 105 the finger guard is always retracted relatively to the die a short distance before the die completes its downward movement, but at this time the arms *i* and 14 have moved so far toward the vertical center line of the die that the knock-off rods *u* and 15 slide 110 back of the heels of said arms and do not actuate them.

A pin *y* on the connecting rod *g* is adapted to engage a tail piece *z* on the locking lever, thereby insuring the engagement 115 of the locking lever with the arm *k* of the lever *j* at the end of the up-stroke of the connecting rod *g*. As the connecting rod moves down, the pin *y* recedes from the tail piece *z*, allowing the locking lever to swing 120 into unlocking position if it is engaged by the knock-off rod *u*. A stop 10 on the link *f* limits the extent of the swing of the locking lever in its unlocking movement.

The upward movement of the lever *d* and 125 arm *k* is limited by a spring-pressed stop 11, thereby insuring that the arm *k* shall not be carried up so far as to prevent the locking lever from latching.

Having now fully described our inven- 130

tion, what we claim and desire to protect by Letters Patent is:

1. In safety stops for machinery, the combination with a reciprocable member the positive operation of which it is desired to automatically arrest, a toggle joint connection between a fixed point and said member, and reciprocatory driving mechanism, of a displaceable device acting when in operative position to form an actuating connection between the driving mechanism and the toggle joint, a guard normally moving with said member but retractable relatively thereto upon meeting an obstruction, and means, actuatable by said guard when so retracted, to move the displaceable device into inoperative position.

2. In safety stops for machinery, the combination with a reciprocable member the positive operation of which it is desired to automatically arrest, a pivoted lever, a link connecting the lever and said member, and reciprocatory driving mechanism, of means to lock said driving mechanism to said lever, a guard normally moving with said member but retractable relatively thereto upon meeting an obstruction, and means, actuatable by said guard when so retracted, to actuate the locking means to disrupt the driving connection between said driving mechanism and lever.

3. In safety stops for machinery, the combination with a reciprocable member the positive operation of which it is desired to automatically arrest, a pivoted lever, and a connection between said member and lever, of a reciprocable link, a pivoted lever adapted to connect said link and the first lever so that the two move in unison to effect the advance movement of said member, a guard normally moving with said member but retractable relatively thereto upon meeting an obstruction, and means, actuatable by said guard when so retracted, to swing the second lever out of connecting position, thereby allowing the movement of the link to be completed without moving the first lever and therefore without positively moving said member to complete its advance movement.

4. In safety stops for machinery, the combination with a reciprocable member the positive operation of which it is desired to automatically arrest, a pivoted lever and a link pivotally connected with said member, of a second link, said links and lever being pivotally connected, reciprocatory driving means connected with the second link, a locking lever pivoted on the second link and normally movable into position to connect the second link with the first lever, a guard normally movable with said member but retractable relatively thereto upon meeting an obstruction, and means, actuatable by said guard when so retracted, to swing

the locking lever into position to disconnect the second link from the first lever.

5. In safety stops for machinery, the combination with a reciprocable member the positive operation of which it is desired to automatically arrest, a pivoted lever, a connection between said member and lever, and reciprocatory driving mechanism, of a two armed lever pivotally carried by said reciprocatory driving mechanism, a hook on one arm adapted to swing into driving engagement with the first lever, a guard normally moving with said member but retractable relatively thereto upon meeting an obstruction, and a knock-off bar carried by said guard and adapted, when the guard is so retracted, to engage the second arm of the two armed lever and swing the hooked arm out of driving engagement with the first lever.

6. In safety stops for machinery, the combination with a reciprocable member the positive operation of which it is desired to automatically arrest, a pivoted lever, and a connection between said member and lever, of a reciprocable link, a pivoted lever adapted to connect said link and the first lever so that the two move in unison to effect the advance movement of said member, a guard normally moving with said member but retractable relatively thereto upon meeting an obstruction, means, actuatable by said guard when so retracted, to swing the second lever out of connecting position and allow the movement of the link to be completed without moving the first lever, means to reciprocate the link, and a device carried by said means and operable, in the return movement of the link, to restore the second lever to its connecting position.

7. In safety stops for machinery, the combination with a reciprocable member the positive operation of which it is desired to automatically arrest, a pivoted lever, and a connection between said member and lever, of a reciprocable link, a pivoted lever adapted to connect said link and the first lever so that the two move in unison to effect the advance movement of said member, a guard normally moving with said member but retractable relatively thereto upon meeting an obstruction, means, actuatable by said guard when so retracted, to swing the second lever out of connecting position and allow the movement of the link to be completed without moving the first lever, means to reciprocate the link, and a device carried by said means and operable, at the beginning of the advance movement of the mechanism, to hold the second lever in connecting position but retractable therefrom, after said advance movement starts, to allow the second lever to be moved out of connecting position as specified.

8. In safety stops for machinery, the combination with a reciprocable member the

positive operation of which it is desired to automatically arrest, a pivoted lever, and a link pivotally connected with said member, of a second link, said links and arm pivotally connected together on a common axis, an arm on said lever, a reciprocatory connecting rod to which the second link is pivoted, the second link in its upward movement adapted to move said arm and thereby move said lever to retract, through the first link, said member, a lever pivoted on the second link and adapted, in the downward movement of the latter, to engage said arm and thereby move the first lever to advance, through the first link, said member, a guard moving with said member but retractable relatively thereto upon meeting an obstruction, and means, actuatable by said guard when so retracted, to move the second lever out of engagement with said arm.

9. In safety stops for machinery, the combination with a reciprocable member the positive operation of which it is desired to automatically arrest, reciprocatory driving means, a chain of driving elements between the driving means and said member, a guard normally moving with said member but retractable relatively thereto upon meeting an obstruction, means, actuatable by said

guard when so retracted, to disrupt said chain of driving elements, a knock-off rod carried by said guard, and means operable by said rod, upon the actuation of said drive-disrupting means, to positively stop the movement of said member. 30 35

10. In safety stops for machinery, the combination with a reciprocable member the positive operation of which it is desired to automatically arrest, reciprocatory driving means, a chain of driving elements between the driving means and said member, a guard normally moving with said member but retractable relatively thereto upon meeting an obstruction, means, actuatable by said guard when so retracted, to disrupt said chain 4 45 of driving elements, a knock-off rod carried by said guard, a ratchet, and a lever carried by one of the driving elements and operable by the knock-off rod, in the retraction of said guard, to engage the ratchet and 50 positively stop the movement of the driving element by which it is carried and thereby stop the movement of said member.

In testimony of which invention we have hereunto set our hands, at Philadelphia, Pa., 55 on this 25th day of July, 1919.

CHARLES FREDERICK WALZ.
FRANCIS DEVELIN MORRIS.
